Primary Examiner — Janice Hallmark(74) *Attorney, Agent, or Firm* — McDermott Will & Emery, LLP(57) **CLAIM**

The ornamental design for a ventilation grill, as shown and described.

DESCRIPTION

FIG. 1 is a perspective view of a ventilation grill showing our new design;

FIG. 2 is a top plan view thereof;

FIG. 3 is a bottom view thereof;

FIG. 4 is a side view thereof; and,

FIG. 5 is a front view, the rear view being exactly the same in appearance, thereof.

The broken lines depict environmental subject matter only and form no part of the claimed design.
